ELECTRIC SWITCH CONSTRUCTION

Monroe Guett and Robert H. Bentley, Hartford, Conn., assignors to The Arrow-Hart & Hegeman Electric Company, Hartford, Conn., a corporation of Connecticut

Application August 4, 1934, Serial No. 738,523

18 Claims. (Cl. 200—168)

This invention relates to electric switches.

More particularly it relates to contact assemblies for electric switches and means for holding contact assemblies within an insulating casing or shell. Recently a demand has arisen for small size electric wiring devices such as switches, attachment plug receptacles, pilot lights, push buttons and the like. Electric wiring devices of the kind just mentioned as heretofore manufactured were of such construction that it is impractical merely to reduce their dimensions in order to make those devices small enough so that several of them could fit in the space originally intended for one device. It has therefore become necessary to find new ways of constructing such devices and particularly electric switches so that their parts might be enclosed within a small casing in order that several such casings might be placed within the space originally used to accommodate one electric wiring device.

Accordingly it is an object of our invention to construct electric switches in such a manner as to reduce their dimensions and enable several of them to be accommodated within a single gang switch box.

Another object of our invention is to provide an inexpensive and sturdy contact assembly for an electric switch which assembly may be easily constructed and quickly put in place and firmly held there.

Another object of our invention is to provide a contact assembly for a double pole electric switch in which a pair of terminals and contacts associated therewith may be mounted as a unit in each end of a switch casing or shell.

Another object of our invention is to provide a switch into the opposite ends of which interchangeable units carrying various combinations of wire terminals and switch contacts may be mounted to adapt the switch for use as an ordinary double pole switch, or in a three way circuit or a four way circuit.

Another object of our invention is to provide an inexpensive and sturdy means to secure and hold the contacts in place within an insulating switch casing in a rigid manner without the use of screws or straps which pass across the rear face of the switch.

Other objects and advantages of our invention will become apparent as it is described in connection with the accompanying drawings. In the drawings:

Figure 1 is a side elevation view of a switch casing partly broken away, and a contact assem-

bly formed according to the principles of our invention.

Figure 2 is an end elevation view of the embodiment of our invention shown in Figure 1.

Figure 3 is a bottom view of the embodiment 5 of our invention shown in Figure 2.

Figure 4 is a bottom view looking into the interior of the switch casing or shell shown in Figure 1, when the shell is empty.

Figure 5 is a longitudinal section view through 10 the embodiment of our invention shown in Figure 1, the section being taken along the line 5—5 of Figure 4.

Figure 6 is a transverse section view of the embodiment of my invention shown in Figure 1, 15 the section being taken along the line 6—6 of Figure 5.

Figures 7 and 8 are perspective views of the contacts which are placed at opposite ends of the insulating casing in the embodiment of our invention shown in Figures 1 to 6.

Figure 9 is an end elevation view of another form of our invention which is adapted for a double pole switch.

Figures 10 and 11 are elevation views of the 25 front and back of the contacts and their mounting which are placed at one end of the embodiment of our invention shown in Figure 9.

Figure 12 is an end elevation view of the opposite end of the embodiment of our invention 30 which is shown in Figure 9.

Figures 13 and 14 are views of opposite sides of the contacts and their mounting which are mounted in said opposite end of the switch casing.

Figure 15 is a bottom view of the embodiment 35 of our invention shown in Figures 9 and 12.

Figure 16 is a bottom view looking into the empty interior of the switch casing of the embodiment of our invention shown in Figures 9 40 and 12.

Figure 17 is a view similar to Figure 16 but with the contacts in place within the casing.

Figure 18 is a longitudinal section view of the embodiment of our invention shown in Figures 45 9 to 17, the section being taken on line 18—18 of Figure 17.

Referring now to the drawings, the switch casing is of insulating material and comprises a hollow shell 1 of generally rectangular prismatic 50 shape having a reduced neck 2 at its top with an opening 3 therein for a switch operating handle or lever 4. The casing may be mounted upon a supporting strap (not shown) in the manner illustrated in the patent of Monroe Guett No. 55

1,909,270, patented May 16, 1933. For the sake of clearness, the switch frame and all the moving parts of the switch mechanism carried thereby have been omitted from the drawings since these parts and this mechanism per se form no part of the present invention. It will be understood, however, that any suitable switch mechanism may be provided for actuating a bridging contact to connect and disconnect the fixed contacts hereinafter to be described. Preferably, a lever operated type of switch for snapping the bridging contact between open and closed position is used.

The switch casing or shell 1 has formed at each end at the bottom edge, arcuate recesses 5 and 15 6 to give access to binding screws 7 and 8, which are threaded into metallic terminal members 9 and 10, within the shell, stationary switch contacts 11 and 12 being mounted on said members.

The terminal members 9 and 10 are somewhat 20 similar in shape but are not identical. Each terminal member has at its lower end opposed laterally extending arms 9a and 10a respectively, the distance between the ends of these arms being equal to the distance between the inside faces 25 of the longitudinal walls of the switch casing 1, so that the engagement between the ends of the arms and the walls of the casing prevent lateral movement of the terminal members. Each terminal member also has at its lower end an ex- 30 tension 9e and 10e respectively, which is adapted to be engaged by the edge of a rear plate 14 of insulating material, the outline of which preferably corresponds with the outline of the bottom of the insulating casing except as to the re- 35 cesses or cut away portions 15, 16, into which the extensions 9e and 10e fit snugly. The engagement of the rear insulating plate 14 with these extensions prevents movement of the terminal members longitudinally of the casing.

40 Each terminal member has arms 9c and 10c respectively extending from the body portion of the terminal member toward one and the same wall of the switch casing. The ends of these arms abut the side of the casing and tend to 45 prevent rocking of the terminal members and thus tend to hold the terminal members in position. Preferably the top edges of the arms 9c and 10c abut the portion of the interior of the top of the switch casing. Upon one of the arms 50 10a, is mounted a fixed switch contact 12 made of thin sheet metal reversely bent into U-shape and positioned so as to be perpendicular to the plane of the terminal member 10. In the central portion of this stationary contact, there is an 55 aperture through which extends a finger 18f of a narrow insulating plate 18, the lower end of which is received between the reversely bent portions of the stationary contact 12. The plane of this plate is perpendicular to the plane of 60 the terminal member 10. The lower extending finger 18f also passes through an aperture provided therefor in the rear plate 14 of the casing. The insulating plate 18 extends upwardly beyond the end of the arm 10c and has a finger 65 18a in extension of its upper end and fitting within the recess 19 provided therefor in the top wall of the casing. The whole of the upper end of the insulating plate 18 fits into a larger recess 20 which is provided in the upper wall of 70 the switch casing. The recess 19 is deeper and is encompassed by the recess 20. The engagement of the fingers 18a and 18f with the top wall of the casing and the rear plate 14 holds the insulating plate 18 firmly in position, and holds 75 terminal 10 against the end wall of the casing.

The terminal member 9 has a stationary contact 11 mounted upon its upper arm 9c and has an insulating plate 22 which passes between the reversely bent portions of the contact 11 and which has a finger 22f extending from the lower end into an aperture provided therefor in the rear plate 14. The whole of the upper end of the insulating plate 22 fits into a recess 24 provided in the top wall of the switch casing and has a finger 22a extending beyond the end of the plate into a deeper recess 25 which is encompassed by the recess 24. The purpose and function of the plate 22 is similar to that of the plate 18.

The movable contact 17 of the switch diagrammatically shown in Figure 5, may be made of a pair of identical laminated sheet metal stampings with spread ends which straddle the stationary contacts and wipe over the outside surfaces of each of the reversely bent parts of the stationary contacts 11 and 12. When the movable contact which preferably is rotatably mounted moves away from the stationary contacts the surfaces of the movable contact wipe over the surfaces of the insulating plates 18 and 22 thus tending to cool and quickly extinguish any arc which may be drawn between the contacts as they separate.

In order to hold the rear plate 14 to the switch casing thin metallic straps 27, 28 run down the 30 side of the casing from the ledge or shoulder 23 formed at the neck 2 and the body of the casing, and have their lower ends turned around the edge of the plate 14 and have fingers 27f, 28f respectively extending into apertures in and near 35 the edge of the rear plate. The top ends of the straps 27, 28 have laterally extending arms 27a, 28a extending into recesses 29 cut in the shoulder or ledge of the casing adjacent the neck 2. Preferably these recesses are of wedge shape and 40 widen as they proceed inward so that when the arms 27a and 28a are spread against the sides of the recesses the straps 27 and 28 will be held from moving away from the sides of the casing. In order to economize on space and to present 45 a smooth side surface for the switch casing, grooves or paths 30 are sunk in the sides of the casing for the straps 27 and 28 so that the surface of the casing and the surface of the strap will be in the same plane. Thus we have provided a simple inexpensive way to hold the rear plate to the switch casing and to hold the contacts and wire terminals fixedly in position without the use of any screw, rivet or similar part such as has been 50 commercially used heretofore.

The construction we have described thus far is suitable for a single pole snap switch, but the principles of the invention may also be applied to a double pole snap switch as will be apparent from the description of the embodiment of our 55 invention shown in Figures 9 to 18.

In this further embodiment of our invention shown in Figures 9 to 18, we use a hollow insulating casing or shell 40 with a reduced neck 41 and an aperture 42 in the top for a switch operating 60 handle or lever 43 as before. In one end of the casing a recess 44 is provided in the bottom edge for the accommodation of a binding screw 45 and an aperture 46 is provided directly above the recess 44 for another binding screw 47. The 65 screws 45 and 47 are threaded into terminal plates 48 and 49 which are mounted upon a rectangular insulating plate 50 whose width is approximately the same as the distance between the inside walls of the switch casing. Engagement 70 75

of the sides of the plate 50 with the inside walls of the casing prevent the lateral movement of the mounting plate 50 within the casing. The shapes of the terminal plates 48, 49 may be observed 5 best by study of Figures 10 and 11. On the opposite side of the mounting plate 50 from the terminal plates 48 and 49 there are four stationary contacts each being of thin sheet metal reversely bent into U-shape, and each provided with fingers 10 extending through apertures in the mounting plate 50 and the fingers of three of the contacts extending into corresponding apertures formed in the terminal plates 48 and 49, the ends of the fingers being peened over to hold the contacts in 15 permanent engagement with the terminal plates or mounting plate 50. One contact is positioned in each of the four corners of the rectangularly shaped mounting plate 50. The stationary contact 20 hand corner of the mounting plate) engages and is in electrical connection with the terminal plate 40. The stationary contact 52 (which is in the upper left hand corner of the mounting plate) is in electrical contact with and engages the terminal plate 48. The stationary contact 53 (which is in the lower right hand corner of the mounting plate) engages with and is in electrical connection with the terminal plate 48. Thus the stationary contacts 52 and 53 are permanently and 30 electrically connected through the terminal plate 48. The stationary contact 54 which is in the lower left hand corner of the mounting plate is electrically connected by a thin strip of copper 55 with the stationary contact 51, this strip of copper 35 being on the opposite side of the mounting plate from the terminal plates 48 and 49 and thus is insulated from the terminal plate 48.

A plate 60 of insulating material, similar to the mounting plate 50 and adapted to be mounted 40 in the opposite end of the casing from the plate 50, has mounted upon one side of it metal terminal plates 58, 59 and on the other side stationary switch contacts 61, 62, 63, 64, these stationary contacts being similar in size and shape to the 45 stationary contacts 51 to 54 inclusive hereinbefore described. The stationary contacts are mounted upon the mounting plate 60 and secured to the terminal plates 58 and 59 in manner and position similar to that described in connection 50 with mounting plate 50. The relative size and shape of the terminal plates 58 and 59 may be observed by examination of Figure 13 from which it will be noted that contacts 61 and 63 are permanently electrically connected to the terminal 55 plate 58 and contacts 62 and 64 are permanently electrically connected to terminal plate 59. The terminal plates 58 and 59 are provided with binding screws 65 and 67 respectively, these screws being accessible through a recess 66 and an aperture 68 respectively in the end of the casing opposite to the binding screws 45 and 47, the arcuate recess 66 being similarly placed to the recess 44 and the aperture 68 being above but slightly offset from the recess 66.

65 Narrow insulated plates 70, 71, 72 and 73 for arc quenching are held in position by stationary contacts 52—54, 51—53, 62—64 and 61—63 respectively in a similar manner to the plates 18 and 22 described in connection with the modification 70 shown in Figures 1 to 8. The ends of each of these plates 70—73 are provided with extending fingers which engage in apertures in the rear plate 76 of the switch and recesses 77, 78, 79, 80 in the inside of the top wall of the casing in similar manner to the insulating plates 18 and 22

whereby they are held fixedly in position, and they hold the mounting plates 50, 60, in position. Downwardly directed extensions 48e and 59e are provided on the terminal plates 48 and 59 and these extensions engage with the recesses 80 and 82 formed in the ends of the rear insulating plate 76 to hold the contacts against longitudinal movement in the casing in a manner similar to that described in connection with the modification shown in Figures 1 to 8. 10

Metal securing straps 27 and 28 are used to hold the rear plate 76 to the casing 40 in a manner like that described in connection with the modification shown in Figures 1 to 8.

In the double pole switch of Figures 9 to 18 15 it is necessary to use two bridging contacts, one located on each side of whatever conventional operating mechanism is used to move the switch contacts; but in the single pole switch of Figures 1-8 only one of the bridging contacts need be employed, though the same operating mechanism can be used.

A sufficient number of contacts are provided in the modification just described to use the switch as a four-way switch. It will be apparent, 20 however, that a person skilled in the art may by eliminating one or more of these contacts use the switch as a three-way or a common double-pole switch, it being remembered that suitable wiring changes for each type of switch will have to be 25 made in the circuit in a manner well known to those skilled in the art. Thus units may be made up with the requisite number of contacts and inserted to fulfill the requirements of the particular usage to which the switch is to be subjected. 30

From the foregoing it will be apparent that the principles of our invention are applicable to single pole, double pole, three way or four way switches and therefore we do not limit our invention except as appears in the following 40 claims to any one type of switch. Obviously many changes in form within the scope of our invention will occur to those skilled in the art.

We claim:—

1. In an electric switch, an insulating casing 45 open at the rear for insertion of switch mechanism and apertured in the front for switch operating means, a combined contact and wire terminal device at an end of the casing, the wire terminal portion of said device being accessible 50 through a recess in the end of the casing, said device being unrestrained against movement lengthwise of the casing by the side walls of the casing but engaging at its top with the inside of the top wall of the casing and having an extension reaching beyond the plane of the back of the casing for holding said device in place, a back plate for the casing engaged by said extension, and means holding said plate to said casing. 55

2. In an electric switch, an insulating casing open at the rear for insertion of switch mechanism and apertured in its front for switch operating means, combined contact and wire terminal means including an insulating plate whose area 65 is approximately equal to that of the inside of the end of the casing, the wire terminal portion of said contact and terminal means being accessible through a recess in the end of said casing, said contact and terminal means being unrestrained against movement lengthwise of the casing by the side walls of the casing but engaging at the top with the inside of the top wall of the casing and having an extension reaching beyond the plane of the back of said casing for 70 75

holding said contact and terminal means in place, a back plate for the casing engaging said extension, and means holding said plate to said casing.

3. In an electric switch, an insulating casing 5 open at the rear for insertion of switch mechanism and apertured in its front for switch operating means, an assembly comprising insulating means having contacts and wire terminals mounted thereon, said terminals being accessible 10 through recesses in the ends of said casing, said assembly being unrestrained against movement lengthwise of the casing by the side walls of the casing but engaging the inside of the top wall of said casing, one of said wire terminals having 15 an extension reaching beyond the plane of the back of said casing, and a back plate for said casing to hold said assembly in place, and means holding said back plate to said casing.

4. In an electric switch, an insulating shell, 20 contact and wire terminal members at opposite ends of said shell, having terminal screws accessible through recesses in said ends, a rear plate for said shell engaging with extensions of said contact and terminal members to prevent lateral 25 and in-and-out movement of said contacts, and separate metal straps on opposite sides of said shell engaging with the edges of said rear plate having laterally extending arms bent to lie in a recess in the top portion of said shell to hold 30 said rear plate in place, the inner portion of said recess being larger than the outer.

5. In an electric switch, an insulating shell, contact and wire terminal members at opposite ends of said shell, having terminal screws accessible through recesses in said ends, a rear plate for said shell engaging with extensions of said contact and terminal members to prevent lateral and in-and-out movement of said contacts, and a ledge around the top of said shell, 35 40 and separate metal straps on opposite sides of said shell engaging with the edges of said rear plate and with said shell at said ledge to hold said rear plate in place, the sides of said shell being provided with channels in which said straps lie.

6. In an electric switch, an insulating shell, contact and wire terminal members at opposite ends of said shell having terminal screws accessible through recesses in said ends, a rear plate for said shell engaging with extensions of said contact and terminal members to prevent lateral and in-and-out movement of said contacts, and a ledge around the top of said shell, and separate metal straps on opposite sides of said shell having reversely bent ends engaging the edges of said rear plate and laterally extending ears bent to seat in recesses in said ledge, to hold said rear plate in place.

7. In an electric switch, an insulating casing, open at the rear for the insertion of switch mechanism and apertured in its front face for switch operating means, combined contact and wire terminal means, the wire terminal portion of said contact and terminal means being accessible 65 through a recess in the end of said casing, said contact and terminal means engaging at the top with the inside of the top wall of said casing and having an extension reaching 70 beyond the plane of the back of said casing, a back plate for the casing engaging said extension to hold said terminal means in place, arc quenching means in engagement with said fixed contacts and interlocking with said rear plate and casing, whereby said arc quenching means

is fixed in position, and means holding said back plate to said casing.

8. In an electric switch, an insulating casing, open at the rear for the insertion of switch mechanism and apertured in its front face for switch operating means, combined contact and wire terminal means, the wire terminal portion of said contact and terminal means being accessible through a recess in the end of said casing, said contact and terminal means engaging at the top with the inside of the top wall of said casing and having an extension reaching beyond the plane of the back of said casing, a back plate for the casing engaging said extension to hold said terminal means in place, an insulating plate 15 engaged with the contact portions of said contact and terminal means and having its ends engaging with said back plate and said casing whereby said insulating plate is fixed in position, and means holding said back plate to said 20 casing.

9. In an electric switch, an insulating casing, open at the rear for the insertion of switch mechanism and apertured in its front face for switch operating means, combined contact and wire terminal means, the wire terminal portion of said contact and terminal means being accessible through a recess in the end of said casing, a back plate for said casing, an insulating plate 25 engaged with the contact portions of said contact and terminal means and lying in a plane perpendicular to the terminal portion of said contact and terminal means, said insulating plate engaging at its ends with the back plate and the 30 inside of the top wall of the casing to hold said contact and terminal means against the end wall of the casing, and means holding said back plate to said casing.

10. In an electric switch, an insulating casing open at the rear for the insertion of switch mechanism and apertured in its front face for switch operating means, combined contact and wire terminal means, the wire terminal portion of said contact and terminal means being accessible through a recess in the end of said casing, said 40 contact and terminal means having an extension reaching beyond the plane of the back of said casing, a back plate for the casing engaging said extension, an insulating plate engaged with the contact portion of said contact and terminal means and having its ends engaging with said back plate and the inside of the top wall of said casing whereby said insulating plate is fixed in 45 position and holds said contact and terminal means against the end wall of the casing, and 50 means holding said back plate to said casing.

11. In an electric switch, an insulating housing having front, back, side and end walls, at least one of said walls being separately formed from the remainder and forming a cover for said housing, said cover when removed permitting insertion of a switch mechanism into said housing, a combined contact and wire terminal device at an end of the housing, the wire terminal portion of the device being accessible through an 65 opening in the end wall, said device being unrestrained against movement lengthwise of said housing by the side walls but engaging at its top with the front wall and at its bottom with a recess in the back wall whereby said device is held in 70 place, and means holding said housing and cover together.

12. In an electric switch, an insulating housing having front, back, side and end walls, at least one of said walls being separately formed 75

from the remainder and forming a cover for said housing, said cover when removed permitting insertion of a switch mechanism into said housing, combined contact and wire terminal means including an insulating plate whose area is approximately equal to that of the inside of the end of the housing, the wire terminal portion of said contact and terminal means being accessible through an opening in the end of said housing, 5 said contact and terminal means being unrestrained against movement lengthwise of the housing by the side walls of the housing but engaging at the top with the top wall and having an extension reaching into a recess in the back 10 wall for holding said contact and terminal means in place, and means holding said cover and housing together.

13. In an electric switch, an insulating housing having front, back, side and end walls, at least one 20 of said walls being separately formed from the remainder and forming a cover for said housing, said cover when removed permitting insertion of a switch mechanism into said housing, an assembly comprising insulating means having contacts and 25 wire terminals mounted thereon, said terminals being accessible through openings in the ends of said housing, said assembly being unrestrained against movement lengthwise of the housing by the side walls but engaging the inside front wall, 30 one of said terminals having an extension reaching into a recess in the back wall, and means holding said cover and housing together.

14. In an electric switch, an insulating housing having front, back, side and end walls, at 35 least one of said walls being separately formed from the remainder and forming a cover for said housing, said cover when removed permitting insertion of a switch mechanism into said housing, a combined contact and wire terminal means, 40 the wire terminal portion of said contact and terminal means being accessible through an opening in the end of the housing, said contact and terminal means engaging at the front with the front wall of the housing and having an extension 45 reaching into a recess in the back wall, arc quenching means in engagement with the fixed contact means and interlocking with said cover and housing, whereby said arc quenching means is fixed in position, and means holding said cover 50 and housing together.

15. In an electric switch, an insulating housing having front, back, side and end walls, at least one of said walls being separately formed from the remainder and forming a cover for said housing, said cover when removed permitting insertion of a switch mechanism into said housing, combined contact and wire terminal means, the wire terminal portion of said contact and terminal means being accessible through an opening 55 in the end of the housing, said contact and terminal means engaging at the front with the front wall of the housing and having an extension

reaching into a recess in the back wall, an insulating plate engaged with the contact portions of said contact and terminal means and having its ends engaging said cover and housing whereby said insulating plate is held fixed in position, 5 and means holding said housing and cover together.

16. In an electric switch, an insulating housing having front, back, side and end walls, at least one of said walls being separately formed from 10 the remainder and forming a cover for said housing, said cover when removed permitting insertion of a switch mechanism into said housing, a combined contact and wire terminal means, the wire terminal portion of said contact and terminal 15 means being accessible through an opening in the end of the housing, said contact and terminal means engaging at the front with the front wall of the housing and having an extension reaching 20 into a recess in the back wall, an insulating plate engaged with the contact portions of said contact and terminal means and lying in a plane perpendicular to the terminal portion of said contact and terminal means, said plate engaging at its ends with the front and back walls of said 25 housing to hold said contact and terminal means against the end wall of the housing, and means holding said cover and housing together.

17. In an electric switch, an insulating housing having front, back, side and end walls, at least one 30 of said walls being separately formed from the remainder and forming a cover for said housing, said cover when removed permitting insertion of a switch mechanism into said housing, combined contact and wire terminal means, the wire terminal portion of said contact and terminal means being accessible through an opening in the end of the housing, said contact and terminal means having an extension reaching into a recess in the 35 back wall of said housing, an insulating plate engaging at its ends with the front and back walls of said housing to hold said contact and terminal means against the end wall of the housing, and means holding said cover and housing together. 40

18. In an electric switch, an insulating housing 45 having front, back, side and end walls, at least one of said walls being separately formed from the remainder and forming a cover for said housing, said cover when removed permitting insertion of a switch mechanism into said housing, an assembly 50 comprising insulating means having contacts and wire terminals mounted thereon, said terminals being accessible through openings in the ends of said housing, arc quenching means in engagement with the said contacts and interlocking with said 55 cover and housing whereby said arc quenching means is fixed in position and impedes movement of said assembly lengthwise of said housing, and means holding said cover and housing together.
